ELECTRODE HOLDER

Bernard Yettner, San Francisco, Calif.

Application January 15, 1938, Serial No. 185,216

2 Claims. (Cl. 219—8)

This invention aims to provide novel means for holding conveniently, an electrode of the kind used in welding. The invention has for one of its objects, the supplying of novel means for actuating the member which grips the electrode. Another object of the invention is to supply a device which, as to general contour, may be held in the hand conveniently, like a pistol, thereby facilitating the welding in difficult places and relieving the wrist and the arm of the workman from strain.

Another object of the invention is to provide novel means whereby the electrode may be retained in alignment with the axis of the holder, or at adjusted angles with respect to said axis, at the will of an operator.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in longitudinal section, a device constructed in accordance with the invention;

Fig. 2 is a top plan of the structure shown in Fig. 1;

Fig. 3 is a longitudinal section like Fig. 1, aside from the fact that the electrode holder has been retracted to working and holding position;

Figs. 4, 5, 6, 7 and 8 are sections taken, respectively, on the lines 4—4, 5—5, 6—6, 7—7 and 8—8 of Fig. 3.

In carrying out the invention there is shown, as depicted in Figs. 1 and 3, for instance, a pistol-shaped body including a barrel 1 and a grip 2, the barrel and the grip made up of material which will resist heat, and at the same time be an insulator against the passage of electricity.

The body 1 and the grip 2 are divided along a longitudinal plane 3, to form laterally separable parts, the barrel 1 including an extension 4 which projects backwardly with respect to the grip 2.

The constituent parts of the body are held together by a securing element 5 connecting the parts of the grip 2, and by a cap 6 which is threaded on the rear end of the extension 4 of the barrel 1, an insulating disk 7 being interposed

between the cap 6 and the end of the extension 4. The parts of the barrel 1 may be held together adjacent to their forward ends by a ring 8, adapted to be slipped over the forward end of the barrel. In the forward end of the barrel 5 there are longitudinal slots 9 lying partly in each half of the barrel, as Fig. 2 will show. In the barrel 1, openings 10 are formed. The openings 10 afford adequate ventilation and avoid overheating. The lower end of the grip 2 also is supplied with ventilating openings 11, as Figs. 7 and 6 will show.

In the barrel 1, behind the slots 9, is disposed a forward guide ring 12, an intermediate guide and abutment ring 14 being located in the barrel, 15 behind the forward ring 12, and a rear guide ring 15 being located in the rear portion of the barrel 1, adjacent to the grip 2. The guide rings 12, 14 and 15 may be mounted in internal seats 16 in the barrel 1, and, as shown in Fig. 4, the 20 said rings may be divided diametrically, as indicated at 17, into halves.

The numeral 18 marks a trigger extended through an opening 19 formed in the grip 2 and in the adjacent portion of the barrel 1, as depicted in Figs. 1 and 5, for instance. The trigger carries at its inner end a segment 21 disposed in the upper part of the grip 2 and in the adjacent portion of the barrel 1. The trigger 18 and its segment 21 are made out of material which is an 30 insulator against heat and electricity, like the barrel 1 and the grip 2. The trigger 18 is mounted to swing on a pivot element 20. The pivot element 20 (Fig. 5) is held against endwise movement within the constituent parts of the grip 2 35 and, preferably, does not extend to the outside of the grip.

A slide rod or electrode holder, generally made of copper, and marked by the numeral 22, is mounted for longitudinal reciprocation in the 40 guide rings 15, 14 and 12. The electrode holder 22 may be of circular cross section, and in order to prevent it from rotating, the electrode holder has parallel flattened surfaces 30 at its rear end, received in a correspondingly shaped opening 31 45 in the rear guide ring 15, the rear guide ring 15, the intermediate ring 14 and the forward ring 12 preferably being formed of metal. The electrode holder or slide rod 22 is supplied with a rack 23, wherewith the segment 21 on the 50 trigger 18 engages.

Intermediate its ends, the electrode holder 22 is supplied with an annular rib 24, which slides in the barrel 1, and also has another function, in that it constitutes an abutment for the rear 55

end of a compression spring 25, the forward end of the said spring engaging the combined abutment and guide ring 14.

At its forward end, the electrode holder 22 has a bore 50 and the electrode holder is slotted longitudinally at its forward end as indicated at 32, to form resilient gripping jaws 26 adapted to engage and hold an electrode 33 in the bore 50. The inner surfaces of the jaws 26 have a plurality of grooves or seats 51 alined with the slots 9 of the barrel 1 and disposed at different angles with respect to the axis of the holder 22.

A flexible conductor 27, which may be flattened in cross section, is connected at its upper end to the electrode holder 22. The conductor 27 extends downwardly within the grip 2 and is connected to a socket 28 on the lower wall of the grip 2, a conductor 29 being engaged with the socket 28 and being in electrical engagement with the conductor 27.

Referring to Fig. 3, the spring 25 slides the electrode holder 22 backwardly, until the rear end of the electrode holder is engaged with the insulating washer 7 within the cap 6. The jaws 26 of the electrode holder, cooperating with the rings 14 and 12, and especially with the ring 12, cause the jaws to grip the electrode 33 and hold it in the bore 50.

Referring to Fig. 1, the operator can press the trigger 18 backwardly, whereupon the segment 21 of the trigger, cooperating with the rack 23 on the electrode holder 22, will advance the electrode holder, the spring 25 being additionally compressed. When the electrode holder 22 is advanced, the jaws 26 loosen their grip on the electrode 33, and the electrode may be removed or adjusted longitudinally in the bore 50; or if the operator prefers, he may place the electrode in any of the seats 51 in the jaws 26 of the holder 22, the electrode then being disposed at adjusted angles to the axis of the holder 22 and being adapted for work, especially inside work, on which the electrode could not be used conveniently if placed in the bore 50, in axial alignment with the holder 22.

When the trigger 18 is released, the parts assume the position of Fig. 3, under the impulse of the spring 25, the electrode 33 entering the slots 9 of the barrel 1, if the electrode is disposed in the dotted positions of Fig. 1, the article being ready for use.

The general construction of the device is such that the electrode 33 may be manipulated and adjusted readily, it being possible for an operator to hold the entire structure in such position that work of practically any sort may be car-

ried out conveniently, even though the work may be in a position in which the work would be inaccessible if a different sort of tool were used. The strain on the arm of the operator is reduced greatly, fatigue is avoided, and a more accurate welding results, with less labor than has been called for heretofore.

Having thus described the invention, what is claimed is:

1. In a welding tool, a pistol-shaped body comprising a barrel and a grip disposed at an angle to the barrel, the body being divided longitudinally to form laterally separable parts, and means for holding said parts together, the barrel being provided with internal annular seats, a forward guide ring, an intermediate guide ring and a rear guide ring mounted in the seats, an electrode holder mounted to reciprocate in the rings and spaced thereby from the barrel, the barrel having ventilating perforations communicating with the space between the holder and the barrel, the grip having ventilating openings, the holder being engaged with the rear guide ring against rotation, the holder having an abutment disposed between the intermediate and rear rings, a compression spring surrounding the holder and engaging the abutment and the intermediate ring, to retract the holder and cause it to grip an electrode, and means on the body and accessible from the grip for advancing the holder to cause it to release an electrode, the last specified means being under the control of an operator.

2. In a welding tool, a pistol-shaped body comprising a barrel and a grip disposed at an angle to the barrel, the body being divided longitudinally to form laterally separable members, the barrel being provided at its forward end with upper and lower slots located partly in each member of the barrel, means for holding the members of the body together, said means comprising a cap on the rear end of the barrel, an electrode holder mounted to reciprocate in the barrel, the holder having in its forward end a slot defining resilient gripping jaws, means for retaining the holder against rotation, thereby to align the slot of the holder with the slots of the barrel, the inner surfaces of the jaws having transverse seats, spring means for retracting the holder to cause an electrode in the seats to enter the slots of the barrel, the cap forming a stop limiting the retraction of the holder, and means accessible from the grip for advancing the holder to release the jaws from an electrode.

BERNARD YETTNER.
